(57) **CLAIM**

I claim the ornamental design for a passenger seating arrangement, as shown and described.

DESCRIPTION

FIG. 1 is a perspective view of the passenger seating arrangement according to the invention;

FIG. 2 is a left-side elevation view of the passenger seating arrangement according to the invention;

FIG. 3 is a right-side elevation view of the passenger seating arrangement according to the invention

FIG. 4 is rear elevation view of the passenger seating arrangement according to the invention;

FIG. 5 is a front elevation view of the passenger seating arrangement according to the invention; and,

FIG. 6 is another perspective view of the passenger seating arrangement according to the invention.
